UNITED STATES PATENT OFFICE.

HANS VOGT, OF BERLIN-WILMEERSDORF, AND JOSEF ENGL AND JOSEPH MASSOLLE, OF BERLIN-GRUNEWALD, GERMANY, ASSIGNEES TO TRI-ERGON, A.-G., OF ZURICH, SWITZERLAND, A CORPORATION OF SWITZERLAND.

LIGHT-MODULATING DEVICE.

Application filed August 18, 1925, Serial No. 51,074, and in Germany February 21, 1922.

The application relates to light modulating devices and more particularly to devices in which the intensity of illumination of a source of light is acoustically-modulated, in 5 a system in which the acoustically-modulated light is caused to photographically form a sound record on a moving film strip or the like. Further, as to some features of the invention, the same relates particularly to 10 improvements in light modulating devices in which the source of light is an evacuated tube containing a certain proportion of a desired gas in which a luminous discharge within the tube is caused, which discharge 15 may be acoustically-modulated by supplying the tube with acoustically-modulated current, such tubes or devices being known as glow tubes or luminous gas discharge tubes.

20 The invention relates in part to arrangements whereby a luminous gas discharge tube may be connected to and supplied from a thermionic amplifier in such a manner that certain difficulties commonly experienced 25 when vacuum tube amplifiers are connected in series with luminous gas discharge tubes will be overcome. As to this it may be noted that gas discharge tubes have, entirely or in part, a negative voltage curve. It, therefore, follows that if such a tube is connected 30 in series with the usual form of vacuum tube amplifier, disproportionalities are caused between the variations in intensities of the 35 luminous discharge and the variations of the electrical current or voltage by which the gas discharge device is operated. An object of the present invention is the provision of means for overcoming or decreasing this difficulty.

40 The invention also relates to improvements in connection with the operation of the acoustically-modulated light by means of amplifying devices in which improved 45 connections are provided between the various parts and in which a loud speaker or other sound reproducing device is additionally provided in the system, by which a person supervising the sound recording system, or supervising the operation of the light modulating apparatus, generally, may determine 50 whether the operation is being effectively performed. Thus in sound recording it has been found desirable to keep the de-

gree of amplification, etc., under control. This may be accomplished by providing a 55 device by which an observer may listen in on the recording system and thereupon cause adjustments to be made in the degree of amplification, etc.

It has been found that means suitable for 60 overcoming the difficulties due to the negative voltage characteristic of the gas discharge tube may be utilized for coupling the sound reproducing device referred to, to the amplifier-gas discharge tube circuit. 65

The invention comprises various combinations of parts and details of construction which will be more fully described in the following specification and which will be particularly pointed out in the appended 70 claims.

In order that the invention may be more fully understood attention is hereby directed to the accompanying drawings forming part 75 of this application and illustrating certain features and embodiments of the invention.

In the drawings Figure 1 is a diagram illustrating the relation between voltage and current of a luminous gas discharge tube;

Fig. 2 is a diagram illustrating the relations between output current and input potential of the usual form of thermionic amplifier connected in series with a luminous gas discharge tube having a negative voltage characteristic; 85

Fig. 3 is a diagrammatic view illustrating connections between an amplifier and a luminous gas discharge tube in a sound recording system comprised within the invention; and 90

Fig. 4 is a diagrammatic view showing a modified form of the invention.

In Figure 1 the characteristic curve, *a*, of a luminous gas discharge device will be seen to be a negative voltage curve, the voltage 95 *V* supplying the tube being indicated by the vertical axis and the current *I* supplied to the glow discharge tube by the horizontal axis. In combination with unstable elements, such as vacuum tube amplifiers, this 100 negative characteristic curve of the glow discharge device may give rise to considerable disturbances. If, for example, a gas discharge tube is connected in series with an amplifier tube of the usual character having 105 a cathode and one grid and one anode, the

current curve of which depends essentially on the penetrating anode potential (i. e., the potential acting through the grid), the following conditions may develop. When the 5 current output of the amplifier increases, the voltage at the gas discharge tube decreases, and the current may continue to increase because of a simultaneously increasing anode voltage of the amplifier. In the case of a 10 diminishing plate current, the opposite effect takes place, since in this case the voltage of the gas discharge tube will be rising. Consequently the current curves of the amplifier connected in series with the glow discharge 15 tube do not correspond, but form a loop which causes considerable disproportionalities in the conversion of electrical waves into variations of light, such for example as in the photographic recording of sound as mentioned above.

This state of affairs is indicated in the diagram of Fig. 2 in which the curve b' may be taken as representing the relations between the plate current and grid potential of 25 the amplifier tube connected in series with a glow discharge tube, in the case of an increasing plate current, while the other curve b'' , forming a loop with curve b' , represents the relation between the plate current and 30 grid potential in such a system when the plate current is diminishing.

This difficulty may be overcome to greater or lesser extent in several ways. Thus, 35 amplifier tubes may be used having a low anode penetration, preferably of less than 5%. Amplifiers having a single plate, grid, and filament and having a sufficiently low anode penetration can, however, hardly be used as a practical matter because the plate 40 potential which is necessary for obtaining an adequate current output in case of negative grid potentials becomes too high. This difficulty may be overcome to a considerable extent by the use of an anode-screening electrode 45 interposed between the plate and grid of the amplifier, with the screening member provided with a greater potential, relative to the filament, than that of the working anode or plate as disclosed in our application 50 Serial No. 458,635, filed April 4, 1921, improvements in electron tubes. With such an arrangement the electro-static lines of force from the working anode or plate through the openings of the grid is greatly 55 decreased while the anode screening electrode, or auxiliary anode, provides a sufficiently large current output for the tube.

The harmful effect of the negative voltage 60 characteristic of the glow discharge tube may also be diminished by connecting ohmic resistances in the output circuit of the amplifier, such resistances being used either alone or in addition to the use of other means such as the anode-screening electrode referred to. 65 Such a resistance reduces the divergence

between the current curves indicated in Fig. 2, since it takes up a part of the injurious potential. Similar results may be obtained if the gas discharge tube is connected in parallel with the amplifier tube, by which 70 the glow discharge tube is fed in the manner indicated in our application Serial No. 545,375, amplifier coupling, filed March 20, 1922, now Patent No. 1,555,301, dated September 29, 1925. In that case the ohmic resistance, which is desired, is afforded by the coupling resistance or resistances through which the B battery current is supplied to the output circuit of the amplifier and to the terminals of the glow discharge device. 80 Suitable connections are described and illustrated in our said Patent No. 1,555,301.

In Fig. 3 we have illustrated a system in which the difficulties referred to are overcome by the conjoint use of an ohmic resistance in the connection between the amplifier and the glow discharge tube, and a protecting or anode-screening electrode in the amplifier. This figure also shows the use of the resistance referred to for coupling an electro-static supervisory telephone or sound 90 reproducing device to the system.

In Fig. 3 the amplifier 1 may be provided with the usual filament 2, grid 3 and plate 4 and in addition with the anode-screening electrode 5 interposed between the plate 4 and grid 3, electrode 5 preferably being of a meshed or grid-like construction.

The luminous gas discharge device 6 comprises an evacuated tube containing a desired proportion of a suitable gas such as, for example, argon, this tube having an anode 7 and a cathode 8. Discharge between these electrodes produces a luminous glow or cloud, chiefly adjacent to the end of the cathode. The intensity of illumination of this cathodic glow is utilized for making a photographic record of varying density upon a moving sensitized film strip or the like. Glow discharge tube 6 is indicated as being contained within a tube 9. The light emitted from the glow discharge tube may be concentrated by a suitable optical system upon a narrow slit (not illustrated), the image of which is projected upon a moving 105 sensitized film strip f .

The output circuit of amplifier 1 may be traced as extending from plate 4 of the amplifier through a variable resistance 10 and a resistance 11 and thence by a conductor 12 to the cathode 8 of the glow discharge tube, the circuit continuing from the anode 7 of the glow discharge tube through battery 13, by conductor 14 back to the filament 2 of the amplifier which may be considered as grounded.

The glow discharge tube will be supplied with amplified acoustically-modulated current when acoustically-modulated potential 130 is impressed upon the input tube terminals

of the amplifier 1, and the light emitted by the glow discharge tube 6 will be correspondingly acoustically-modulated.

The auxiliary electrode 5 of the amplifier 5 is connected by conductor 15 to a point of positive potential in the source 13. The screening electrode 5 of the amplifier will, therefore, be of a higher potential than the plate 4, since the latter is connected to the 10 positive terminal of the source 13 through a considerable resistance which may comprise the internal resistance of the glow discharge tube 6 or the resistances 10 and 11, or both. The difficulties due to the negative voltage 15 characteristic of the glow discharge tube are, therefore, overcome in the embodiment of the invention here illustrated by the use of the screening electrode 5 together with the use of the resistance 11 and as much of the 20 variable resistance 10 as may be included in the plate circuit of the amplifier.

A resistance 16 of large value is shown as connected in parallel with the output of amplifier 1. Accordingly, a small current will 25 continue to flow through the gas discharge tube 6, from battery 13, even when for any reason the impedance of the amplifying tube 1 becomes infinitely high. This resistance 16 is used to prevent complete interruption of 30 the current feeding glow discharge tube 6 in any case, because interruption of this current would entail difficulties in the immediate restarting of the glow discharge current through tube 6.

35 The sound reproducing device previously referred to preferably takes the form of a condenser telephone type of loud speaker indicated at 17, which may be mounted within a sound proof enclosure indicated at 18. The 40 condenser telephone comprises a fixed plate element 19 and a movable plate element in the form of a diaphragm 20. This telephone is connected in parallel with resistances 10 and 11 by means of conductors 21 and 22, a condenser 23 being positioned in 45 one of these connections. The variable resistance 10 enables the volume of the sound produced by the condenser telephone 17 to be adjusted as desired, a connection 24 extending 50 from conductor 21 to an adjustable contact on the resistance 10. A resistance 25 is employed to drain off any electric charge which may tend to accumulate upon the otherwise insulated coating of the condenser 55 telephone, this resistance being connected from conductor 21 to conductor 14, and thence to the ground.

It will be obvious that the condenser telephone 17 will be operated by and in accordance with the acoustically-modulated current in the output circuit of the amplifier 1 and an observer or supervisor of the recording process may thus be enabled to determine 60 whether modulation of the light of glow upon lamp 6, and the photographic recording

upon film 7, are being properly carried out. The operator in the listening-in chamber 18 may adjust the degree of amplification of the system from time to time as desired by suitable means.

70 Fig. 4 is a somewhat simplified diagram illustrating an embodiment of the invention in which the amplifier 1^a is not provided with the anode-screening electrode 5, which has been described in connection with Fig. 3. The luminous gas discharge tube 6^a is connected in series with the output terminals of the amplifier 1^a, the source of potential 13^a and the resistance 11^a being included in the circuit. The telephone or loud speaker 17^a is connected in parallel with resistance 11^a, this sound reproducing device preferably being a loud speaker of the condenser telephone type, as described above. With this 75 form of apparatus the resistance 11^a alone is depended on for overcoming the harmful effects of the negative voltage curve of the gas discharge device and this resistance is additionally used as a means for coupling the telephone 17^a.

80 90 We claim:

1. In light-modulating devices, the combination of a luminous gas discharge tube having a negative voltage curve, a thermionic amplifier having input and output terminals, a source of potential, a resistance, and means for connecting the amplifier output terminals, discharge tube, source and resistance in series, said resistance being adapted to largely overcome the effect of 100 the negative voltage characteristic of said discharge tube in causing disproportionality between the variations of intensity of luminous discharge of said tube and the variations of potential at the input terminals of said amplifier.

105 110 115 2. In light-modulating devices, the combination of a luminous gas discharge tube, a thermionic amplifier having anode, cathode, grid and an anode-screening electrode, a source of potential, a resistance, and means for connecting the amplifier anode and cathode, discharge tube, source and resistance in series and for connecting said screening electrode to a point in said connections of higher potential than that of said anode.

120 125 3. In light-modulating devices, the combination of a luminous gas discharge tube, a thermionic amplifier having anode, cathode, grid and an anode-screening electrode, a source of potential, means for connecting the positive terminal of said source through said discharge tube to said anode and for connecting the negative terminal of said source to said cathode, and a connection between said screening electrode and a point in said source of higher potential than that of said amplifier anode.

120 4. In light-modulating devices, the combination of a luminous gas discharge device

- 4
- having a negative voltage curve, a thermionic amplifier tube, having input and output terminals therein, a source of potential, said source being connected to the output terminals of said amplifier tube and the latter being connected to supply current to said gas discharge device, and means adapted largely to overcome the effect of the negative voltage characteristic of said discharge device in causing disproportionality between the variations of intensity of luminous discharge of said device and the variations of potential at the input terminals of said amplifier.
5. In light-modulating devices, the combination of a thermionic amplifier having an input circuit and an output circuit, a luminous gas discharge device and a resistance, both in said output circuit, and a sound reproducing device in shunt with said resistance.
6. In light-modulating devices, the combination of a thermionic amplifier having in-
- put and output terminals, a high resistance connected across said output terminals, a 25 second resistance and a luminous gas discharge device connected in series with said output terminals, and a source of potential connected to said output terminals.
7. In light-modulating devices, the combination of a thermionic amplifier having an output circuit, a luminous gas discharge device and a resistance, both in said output circuit, and a condenser telephone connected across said resistance. 30
8. In light-modulating devices, the combination of a thermionic amplifier having output terminals, a variable resistance, a luminous gas discharge device and a source of potential in series with said terminals, a 35 sound reproducer, and means for connecting the latter across a greater or less amount of said resistance.
